UNITED STATES PATENT OFFICE.

ISAAC C. POPPER, OF NEW YORK, N. Y., ASSIGNOR TO THE THEROZ COMPANY, OF NEW YORK, N. Y., A CORPORATION OF DELAWARE.

PORTABLE STOVE.

Application filed August 29, 1919. Serial No. 320,610.

To all whom it may concern:

Be it known that I, ISAAC C. POPPER, a citizen of the United States, residing at New York city, in the county of New York and 5 State of New York, have invented certain new and useful Improvements in Portable Stoves, of which the following is a specification.

My invention relates to an improvement 10 in portable stoves designed more particularly for use with solidified alcohol or the like as a fuel, the stove being particularly adapted for use by touring parties and picnickers, although obviously it can be used 15 for any purpose where a stove is required, it being light, capable of folding in comparatively small space, and, due to the fact that it presents no obstructions in its interior, fuel and other articles can be packed 20 therein as in a valise, and carried when not in use.

This invention comprises a hollow body portion with a perforated dished area formed on the top, through which the flame 25 circulates against and beneath the articles being heated. It further consists in a stove having folding legs, and a catch having the double function of holding the legs in either extended or folded position. This invention further consists in a light, portable, 30 sheet-metal stove having a hollow body portion with a hole to receive the burner in the bottom, and a perforated area above this hole slightly dished inwardly or concaved, 35 whereby to receive and circulate the flame from the burner against and beneath the article to be heated.

In the accompanying drawings:

Fig. 1 is a view in perspective; 40 Fig. 2 is a longitudinal sectional view; Fig. 3 is a transverse section; Fig. 4 is a detail in section; and Fig. 5 is a fragmentary bottom plan view.

The main or body portion of the stove 45 consists preferably of a sheet-metal bottom 1, a top 2, a perforated back and ends, 3 and 4 respectively, and a front 5, the back, ends and front being conveniently bent from 50 the same sheet of metal forming the top. In the construction illustrated, the bottom 1 has depending flanges 6 at the edges by which it is secured to the lower edges of the back, ends and front, thus forming the 55 body or main portion of the stove.

The front is provided with an opening 7 throughout the major portion of its length and breadth, whereby to gain access to the open interior of the stove. This opening is adapted to be closed by a perforated door 60 8 having its lower edge connected throughout its length by a hinge 9 to the lower edge of the opening.

The door 8 may be fastened by two catches 10 pivoted at their lower ends to the inner 65 face of the door 8, and these catches are provided each with a button 11 which extends through the slot 12 in the door to the outside, where they may be easily manipulated. A keeper 13 embraces the free end 70 of each catch from the rear, and the space between the keeper and the door is reduced at one end (preferably the inner end) and as shown in the detail, Fig. 4, the metal forming this reduced portion is offset as at 75 13' to receive the inner end 14 of the button whereby to hold the catch frictionally when in the position of locking the door.

These catches take under the upper edge 80 of the opening 7, which is preferably reinforced by an angle-iron strip 7' against which the door closes, so that the outer surface of the door when closed is always flush with the outer surface of the front of the stove.

A handle 15 is pivoted preferably on the door as a convenient means of carrying the stove.

The particular stove illustrated has a 85 place for two burners, although obviously this number might be varied, and a hole 17 is formed in the bottom to receive and center the fuel can or burner 18 as illustrated, thus holding it in the proper position and preventing it from sliding or becoming displaced.

The metal in the top is dished or concaved 90 as at 19, and the center immediately over the fuel can or burner is cut out, forming an opening 20, so as not to obstruct the 100 flame. The remaining dished or concaved portion is provided with perforations 22, so that a pan or kettle placed on the top over a burner forms a closure or partial closure over the dished or concaved portion, thus 105 causing the flame which comes up through the central opening 20, in direct contact with the bottom of the cooking utensil, to return through perforations 22, and finally out through the perforations at the sides or ends 110

of the stove. In this way, practically every particle of the heat is applied directly to the bottom of the cooking utensil by the passage of the flame up through the center hole 20, and its spreading and returning through the perforations 22, and in this way I have found that the heating or cooking can be greatly expedited.

The stove is preferably mounted on legs 21', pivoted at the ends, so that they may be extended into vertical position and held against the depending end flange of the bottom when in use, or folded under flat against the bottom, they having upturned lugs 23 at their ends which pass through clearance slots 24 at the corners of the bottom, where they are held pivotally in position by rivets 25.

A catch 26 is pivoted to the bottom in position to swing securely against the center of the leg when the latter is extended out, thus holding the leg between it and the end flange. This catch 26 is offset at 27 to enable it to embrace the leg when folded in, so that the catch has a double function, namely it forms a brace for the leg when extended, and a means of holding it flat against the bottom when folded.

The space inside of the stove may be utilized to carry fuel or cooking-utensils, it being possible to pack it full when being carried about, at which time, of course, the legs are folded under and fastened flat against

the bottom and the stove is carried by the handle. When in use, the legs are extended 35 and fastened in a vertical position by the catches, the door is opened, and the fuel cans are opened and placed in position in the holes provided for them, the fuel is ignited, and the stove is ready for heating or 40 cooking.

I claim:

1. A stove comprising a top, a bottom, front, perforated back and ends, the front having an opening and a perforated door 45 hinged at one edge thereof, means for fastening the door when closed, the top having a depressed opening with surrounding perforations through which the flame from the burner passes, and the bottom having a hole 50 immediately below the opening to receive, center, and hold the burner.

2. A stove made of sheet-metal comprising a top, a bottom, front, back and ends, the front having an opening and a door 55 hinged at one edge thereof, means for fastening the door when closed, said means comprising a pivoted latch, a thumb-button connected therewith, the door having a curved slot to receive said button, and a 60 keeper for the latch having means to frictionally hold the latch in the located position.

In testimony whereof I affix my signature.

ISAAC C. POPPER.
